UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

CUFF-PRESS.

1,042,752.

Specification of Letters Patent. Patented Oct. 29, 1912.

Application filed March 1, 1911. Serial No. 611,712.

To all whom it may concern:

Be it known that I, WILLIAM BARTHOLOMEW, a citizen of the United States, residing at Chicago, county of Cook, State of Illinois, have invented certain new and useful Improvements in Cuff-Presses, of which the following is a specification, reference being had therein to the accompanying drawing.

This invention relates to a cuff press and particularly to a construction in which the goods supporting member is moved relative to the pressing head.

The invention has for an object to provide a novel and improved construction by which a rod for reciprocating the goods support is mounted for lateral oscillation in order that the support may be withdrawn laterally from alinement with the head and, when placed in such alinement, be forced into contact therewith by a reciprocation of its supporting rod.

Other and further objects and advantages of the invention will be hereinafter set forth and the novel features thereof defined by the appended claims.

In the drawings—Figure 1 is a front elevation of the press; Fig. 2 is a side elevation thereof with the goods support withdrawn; Fig. 3 is a horizontal section on line 3—3 of Fig. 2; and Fig. 4 is a rear elevation showing the flexible steam connections with the head and goods support.

Like numerals of reference refer to like parts in the several figures of the drawings.

The numeral 10 designates a standard of any desired construction which is provided at its upper end with the support 11 for the pressing head. In Fig. 1, this support is duplicated in order to permit an alternate pressing operation of the pressing members. These members may be of any desired construction, for instance such as shown in my application filed July 20, 1910, Serial No. 572,908, which illustrates the central yielding head 12 pivotally mounted at 13 to a slightly yielding yoke 14 which carries at its lower ends the movable side heads 15. The yoke 14 is held under tension by a spring 16 and the side heads are pivotally connected to the yoke 14 at 17 and also to pivoted links 18 at opposite sides thereof. The lower ends of the side heads are also connected by links 19. Extending over the pressing heads 12 and 15, a flexible plate 20 is disposed, which is adapted to be forced in- ward in the movement of the heads toward each other to prevent a ridge or other disfiguration of the articles pressed between the members of the head. Each of these members is suitably heated and may comprise a steam chest, connected for instance by means of an inlet pipe 21 having flexible connections 22 with the head members 12 and 15, and also a connection 23 extending to the goods support 24. From this support, a flexible connection 25 extends to an exhaust connection 26 communicating with an exhaust pipe 27. Flexible exhaust pipes 28 also extend from the head 12 to the connection 26 and similar pipes 29 extend from the side heads 15 to this exhaust connection, as shown in Fig. 4. By these connections, steam is applied both to the goods support and to the pressing heads coöperating therewith.

For the purpose of reciprocating the goods support 24, it is mounted upon an operating rod 30, as shown in Figs. 1 and 2, and this rod is connected with a treadle mechanism 31 of substantially the construction shown in my Patent No. 952,721, dated March 22, 1910, wherein the treadle is shown as connected with the rod 30 by a yielding connection 32 and a pivoted joint 33. The rod 30 is pivoted to the yielding connection at 34 and is slidably mounted in a sleeve 50 pivoted upon a bracket 35, as shown at 36, in order to swing laterally into or out of alinement with the fixed head of the press. This swinging movement is guided by a yoke 37 adapted to be secured to the standard in any desired manner, for instance by a bolt 38 as shown in Fig. 3, to limit the outward movement of the operating rods 30 of each of the heads. This operating rod has secured thereon a block 39 slidably mounted in the guides 37 and is provided with a head 40 having lugs 41 upon which the goods support 24 is mounted by means of the depending bolts 42 extending therethrough. The goods support is pivotally mounted at 43 and provided with a handle 44 by which it may be shifted laterally of the pressing head. The operating rod 30 is threaded at its upper end 45 and provided with adjusting nuts 46 by which the goods support 24 may be properly adjusted to secure accurate contact with the pressing members of the head. The rods 30 are here- in shown as adapted to be operated in alter-

nation by the treadles 30 through the levers 46 which are operated by the arms 47 carried by the treadles. These levers are pivotally mounted at 48 and adapted to engage the pivotal treadle connection with the operating rods, as shown at 49, to break the toggle joint and allow the descent of the goods support, substantially as shown in my Patent #952721.

In the operation of this construction, it will be seen that the goods support is adapted to be withdrawn from the pressing head and swung outward toward the operator in order to permit the convenient removal of articles already pressed and the application of other articles to be pressed. The support is then swung into alignment with the pressing head upon the standard and subsequently forced upward into contact therewith by means of the treadle which gives the necessary yielding tension to secure a proper pressing operation. In the form of the invention shown, the goods support is adapted to be alternately operated so that while one is in contact with the pressing head, the pressed goods may be removed from the other and new goods applied thereto. This construction also provides for a proper guiding in the outward swinging of the goods support and a pivotal mounting thereof so that it may be maintained in horizontal position. The structure presented also obviates the necessity of using a sliding goods support upon a reciprocating operated rod and provides means by which the support is brought into guiding alignment with the pressing head when the rod is moved inward into alignment with said head.

Having described my invention and set forth its merits what I claim and desire to secure by Letters Patent is—

1. In a cuff press, a standard, a pressing head thereon, an oscillating and reciprocating member having a sliding and a pivotal connection thereon, a goods support pivotally mounted on the upper end of said member, a yoke carried by the standard surrounding said member, a block carried by said member slidably mounted in said yoke, and a treadle for operating said member.

2. In a cuff press, a standard, a pressing head thereon, an oscillating reciprocating

member having a sliding and pivotal connection with said standard, a goods support 55 pivotally mounted thereon and capable of maintaining parallelism with said head, a treadle for operating said member, and a guide for the pivotal movement of said member.

3. In a cuff press, a standard, a pressing head thereon, an oscillating reciprocating member pivotally and slidably mounted, a goods support pivotally mounted on said member, a treadle for operating said member, a guide, and a block carried by said member to travel in said guide.

4. In a cuff press, a standard provided with a pressing head, an oscillating reciprocating pressing rod, a goods support pivoted 70 at the upper end thereof, a sleeve surrounding said rod and pivotally mounted upon said standard, and means for reciprocating said rod.

5. In a cuff press, a standard provided 75 with a pressing head, an oscillating reciprocating pressing rod, a goods support pivoted at the upper end thereof, a sleeve surrounding said rod and pivotally mounted upon said standard, and a pivoted treadle 80 having a yielding connection with said rod.

6. In a cuff press, a standard, a pressing head thereon, an oscillating reciprocating member having a pivotal and sliding connection with said standard, a goods support 85 pivotally mounted on said member capable of being maintained in a horizontal position, means for oscillating said member and support carried thereby, a guide, and a block carried by said member working in said 90 guide.

7. In a cuff press, a standard, a pressing head thereon, an oscillating and reciprocating member having a sliding and a pivotal connection thereon, a block secured to said 95 member, a yoke carried by the standard surrounding said block, a goods support pivotally mounted on said block, and a treadle for operating said member having a yielding connection therewith.

In testimony whereof I affix my signature in presence of two witnesses.

WILLIAM BARTHOLOMEW.
